UNITED STATES PATENT OFFICE.

FRANCIS LINDENTHALER, OF SAYBROOK, CONNECTICUT.

HEADLIGHT.

Application filed November 27, 1923. Serial No. 677,297.

To all whom it may concern:

Be it known that I, FRANCIS LINDENTHALER, a citizen of the United States, residing at Saybrook, in the county of Middlesex and State of Connecticut, have invented new and useful Improvements in Headlights, of which the following is a specification.

This invention relates to headlamps of the character generally used on motor operated vehicles, and it is the purpose of the invention to improve the construction of said lamps, so that the duty of replacing new bulbs or repairing the electrical connections with the bulbs are materially facilitated.

In carrying out the invention, it is my purpose to provide a headlamp wherein the rear wall of the lamp casing includes a detachable portion which supports the electric light and socket, and the connection between the detachable portion and the lamp casing is such that said portion can be quickly and easily detached from the casing, so that the bulb can be readily replaced, or an inspection and repair made of the electrical connection with the bulb should the occasion require.

The nature and advantages of the invention will be better understood when the following detailed description is read in connection with the accompanying drawings, the invention residing in the construction, combination and arrangement of parts as claimed.

In the drawings forming part of this application, like numerals of reference indicate similar parts in the several views, and wherein:

Figure 1 is a vertical sectional view through a headlamp constructed in accordance with one embodiment of the invention showing the association of the parts.

Figure 2 is a view similar to Figure 1 showing the removable portion of the lamp casing separated from the latter, and the bulb partly retracted from the lamp casing.

Figure 3 is a sectional view taken on the line 3—3 of Figure 1.

Figure 4 is a plan view of the retaining disk or plate for the removable portion of the lamp casing.

Figure 5 is a view in elevation of the removable portion of the lamp casing.

Figure 6 is a view similar to Figure 1 of a modified construction.

Figure 7 is a view similar to Figure 2 of said modified construction.

Figure 8 is a view in elevation of the removable portion of the lamp casing.

Referring to the drawings in detail, and particularly to Figures 1 to 5 inclusive, I have shown a headlamp of the drum type now usually employed on motor operated vehicles. The lamp casing is indicated at 10 and includes a rear wall, the front of said casing being closed by means of the usual lens 11. The reflector is indicated at 12, the electric light bulb at 13, and the usual socket for said bulb is indicated at 14. All of these features are of the same general construction as those now in use, except that the rear wall of the lamp casing includes a removable portion 15 which constitutes the center of this wall, and is of cap like formation as clearly shown in Figures 1 and 5. The removable cap like portion 15 is adapted to fill the enlarged central opening formed in the rear wall 16 of the casing when the parts are associated, while the cap 15 itself is provided with a central opening surrounded by a flange 17 to accommodate the electric light socket 14. The cap like portion 15 is formed with an annular bead 18 which bears against the outwardly flared or curved portion 19 of the rear wall when the parts are assembled as shown in Figure 1. The annular portion 20 of this cap is formed on its inner edge with substantially hook like elements 21 which are designed to engage the edge 22 of the enlarged opening formed in a retaining plate or disk 23 which is secured to the inner side of the rear wall 16 of the lamp casing as shown in Figure 3. This plate or disk 23 can be secured to the lamp casing in any suitable manner and is formed with an enlarged central opening to receive the lamp socket 14, to cooperate with the removable cap 15 to hold the latter operatively associated with the lamp casing proper.

There are preferably three of these hook like elements 21 carried by the cap, and for each element 21, the edge 22 of the opening of said plate 23 is formed with a notch 24, so that the elements 21 can be initially positioned in said notches incident to the association of said parts, and the cap 15 subsequently turned in either direction to cause the elements 21 to embrace the edge 22 of the plate as shown. The tension of these elements 21 holds the cap 15 in place.

By reason of the construction shown and thus far described, it is obvious that the cap 15 can be quickly and conveniently separated from the rear wall 16 of the lamp casing, and separated from said casing in the manner shown in Figure 2, so that access may be readily had to the electric light bulb to replace the latter, or to repair any of the electrical connections as the occasion may require. Again, by reason of these facts, the necessity of removing the lens 11 and its retaining flange from the lamp casing, which is now the usual method of gaining access to the electric light bulb 15 is eliminated, and the necessary repairs to the lamp more quickly accomplished. It is only necessary to give the cap 15 a slight turn in the proper direction to bring the hook like elements 21 into the notch 24 of the retaining plate 23 in order to remove the cap from the rear wall of the lamp casing, and inasmuch as the electric light socket 14 is connected with this cap, it is of course simultaneously removed from the casing therewith.

In Figures 6 to 8 inclusive, I have shown the invention employing a lamp of a different configuration, and wherein the lamp casing is substantially dome shaped and indicated at 28. This casing is provided with an enlarged opening at the rear thereof, and the edge of this opening is offset inwardly as at 29 thereby providing a shoulder 30 which surrounds the opening referred to. Carried by the casing 28 are headed studs 31 there being preferably three of these studs equidistantly spaced about the said opening and in close proximity to the shoulder 32. The opening at the rear of the lamp casing is in this instance closed by means of a removable plate which may be properly termed a cap indicated at 32, and which cap is provided with a central opening surrounded by a flange 33 which receives and embraces the electric light bulb socket 34. The electric bulb is of course indicated at 35 and is associated with the socket in the usual well known manner. The cap 32 is designed to conform to the curvature of the casing 28, and when associated with the latter, the edge 36 of said cap bears against the annular shoulder 30 of said casing, and is supported by the inwardly offset flange 29 above referred to.

Projecting from the edge 36 of this cap at equi-distantly spaced points are hook like elements 38 which are also slightly offset as shown to lie upon the outer surface of the lamp casing 28 and to extend beyond the shoulder 30, these hook like elements 38 are adapted to receive the headed studs 31 carried by the lamp casing to hold the cap associated with the latter. It is only necessary to arrange the hook like elements in position to receive the headed studs 31 incident to the positioning of the cover or cap 32 on the flange 29, and subsequently turn the cap a slight distance toward the right in order to position the hook like elements over the studs 31.

In this form of the invention the bulb can be just as easily retracted from the lamp casing as in the form hereinabove described, in that it is only necessary to give the cap 32 a slight turn to the left to disengage the hook like elements 38 from the headed studs 31 whereupon the cap 32 together with the electric light socket 34 and bulb 35 can be removed or separated from the lamp casing for the purpose mentioned.

While it is believed that from the foregoing description, the nature and advantages of the invention will be readily apparent, I desire to have it understood that I do not limit myself to what is herein shown and described, and that such changes may be resorted to when desired as fall within the scope of what is claimed.

Having thus described the invention, I claim:

The combination with an automobile lamp having an opening in its rear end, of an annular plate carried by the rear wall of the casing and surrounding the opening therein, and provided with a plurality of spaced notches and also provided with a central opening, a cap for supporting an electric light bulb within the casing and removably received in the open end thereof, a plurality of hook like elements carried by the cap and adapted to be passed through the openings in the plate and subsequently engaged with the latter upon rotation of the cap.

In testimony whereof I affix my signature.

FRANCIS LINDENTHALER.
